UNITED STATES PATENT OFFICE.

RACHEL TEAMER, OF EVANSVILLE, INDIANA, ADMINISTRATRIX OF
WILLIAM TEAMER, DECEASED.

JAR-FASTENING.

SPECIFICATION forming part of Letters Patent No. 469,985, dated March 1, 1892.

Application filed February 16, 1891. Serial No. 381,615. (No model.)

To all whom it may concern:

Be it known that WILLIAM TEAMER, formerly a citizen of the United States, residing at Evansville, Vanderburg county, Indiana, but now deceased, did during his lifetime invent certain Improvements in Fastenings or Retainers for Fruit-Jar Caps, of which the following is a specification.

The object of this invention is to construct a simple but effective form of fastening or retainer for the caps or covers of fruit-jars, the fastener comprising but two parts—namely, a lever and a bail—and the invention having reference to the special form and mode of hanging of the bail and to the special form and bearing of the lever.

In the accompanying drawings, Figure 1 is a perspective view of the improved fastening as it appears when confining the cover upon the jar. Fig. 2 is a vertical central section through Fig. 1, and Fig. 3 is a side view of Fig. 1.

Similar letters refer to similar parts throughout the several views.

25 A designates the body of a preserve-jar, and B the annular mouth of this jar, having a horizontal shoulder, upon which is a rubber gasket-ring H, and within this ring is a raised annular lip a. (Shown in Fig. 2.)

30 In the side of the mouth B are depressions C C, which are diametrically opposite each other and in which are sprung the pivotal angular ends h h of a bail E. This bail, which is preferably made of round wire, is formed 35 with angular arms, as shown in Figs. 1 and 2, springing from two parallel guides or braces k k, terminating in a pivotal fulcrum i for a locking-lever F, the bail E being free to swing and spring over a convex cap or 40 cover D, and also over the edge of the mouth of the jar when the cover is to be removed.

To the fulcrum-joint or crotch i of the bail is pivoted the bell-crank lever F, the bill or shorter arm e of which is tapered from 45 the head e' and forms with the handle an acute angle, so that when the cover is locked in place on the mouth of the jar the point of the bill e bears in a depression b in the raised nipple portion d of the cover and the 50 handle part of said lever impinges against the margin of the mouth B of the jar. In this position of the lever F the point i is a little to one side of a vertical line passing

through the center of the jar, and the parts are held by the natural recoil of the spring-bail in the positions shown in Fig. 3. It will be observed that the lever F is prevented from lateral displacement by the parallel limbs k k of the bail, which also serve as guides for the lever while manipulating it. 55 As the bell-crank lever and bail in their action form a toggle-joint, a powerful pressure can be brought to bear upon the cap and the tight sealing of the jar is insured. The formation of the central recess in the cap D for 60 the action of the lever insures the proper bearing of the latter upon the cap without necessitating any special adjustment of the cap on the jar before sealing the same, and the bail hung to the jar provides a handle 65 whereby the jar when filled with hot fruit can be conveniently carried from place to place.

Having described the invention of the said WILLIAM TEAMER, what is claimed and desired to be secured by Letters Patent is— 75

1. The combination of the jar and its cap with the pivoted bail having a converging upper portion terminating in opposite straight legs located close together, with connecting-crotch at the top, and a bell-crank lever pivoted to said crotch at right angles to the bail and swinging between and confined laterally by the parallel legs of said bail, said lever bearing with its short arm upon the top 80 of the cap, substantially as specified.

2. The combination of the jar having recesses in its opposite sides, the bail having angular pivot ends adapted to said recesses and a converging upper portion terminating 85 in opposite straight legs located close together, with connecting-crotch at the top, a bell-crank lever hung to said crotch at right angles to the bail and swinging between and confined laterally by the legs of said bail, and a cap having in the top a central recess which receives the bearing end of the short arm of said lever, substantially as specified. 95

In testimony whereof I have signed my name to this specification in the presence of 100 two subscribing witnesses.

RACHEL TEAMER,
Adm^x. of estate of William Teamer, deceased.
